UNITED STATES PATENT OFFICE.

GEORGE W. HORNE, OF NEW YORK, N. Y., ASSIGNOR TO A. A. KNUDSON,
OF SAME PLACE.

FEED-BAG FOR HORSES.

SPECIFICATION forming part of Letters Patent No. 293,250, dated February 12, 1884.

Application filed May 9, 1883. (No model.)

To all whom it may concern:

Be it known that I, GEORGE W. HORNE, a subject of the Queen of Great Britain, and a resident of New York, in the county and State of New York, have invented certain new and useful Improvements in Feed-Bags for Horses, of which the following is a specification.

The object of my invention is to provide improved means for ventilating feed-bags for horses, the improvements being especially applicable to feed-bags in which one end is supported by the harness, so as to be maintained in proximity to the lower portion of the neck of the animal, and the other end supported near the nose of the animal, so that the position of the feed in the bag (when the latter is partly filled) may be controlled by the movements of the horse's head.

The ventilator forming the subject of the present application consists of two or more vertical tubes, the inner ends of which terminate near the nostrils of the horse, while the upper ends open outward. Such tubes may be constructed of rubber, leather, or other suitable material, and they are of sufficient size to both prevent any possibility of their becoming clogged and to allow free circulation of the air.

In the accompanying drawings, Figure 1 is a side elevation of a nose-bag, illustrating my invention as applied to a horse's head, showing the same in an elevated position in full lines. The dotted lines show the same in the lower position. Fig. 2 illustrates a modification in the construction of the ventilating portion.

Referring to these figures, A represents a cylindrical sack or bag, of canvas or other suitable material, one end of which is preferably closed by means of a semicircular block of wood or other stiff material, as shown at a. The other end is closed by a seam, a'. The lower side of the bag may be formed or rounded at this end, as found convenient. Upon the upper side of this end of the bag is formed a longitudinal slit, through which it is designed that the horse's nose shall pass. The main portion of the bag may be formed from a

single piece of cloth sewed together upon the upper edge. The opening or slit b is formed by simply leaving an open place in this seam. A cord, c, is secured to the wooden section a, and may be tied to the hames or to the saddle as desired, for supporting that end of the bag. 55 A similar cord, d, is secured to one side of the nose end of the bag, and passes over the horse's head to the opposite side of the bag, where it is tied, the length of the cord being sufficient to bring the bag into such a position that the 60 horse's nose will enter the lateral opening. At the front or nose end of the bag is formed a ventilator, which, as shown in Fig. 1, consists of short rubber tubes, e' e'', covered with coarse canvas or other cloth. The inner ends 65 of these tubes may, if desired, be beveled to prevent any possible chafing of the horse's nose. The number and size of these tubes may be varied as desired. The position of the bag when the horse's head is down is indicated in dotted lines, and the length of the bag is preferably such that it will not be stretched tight when the horse's head is in its forward position.

Fig. 2 shows a modification in the plan 75 of ventilating the bag, which consists in forming a transverse slot in the nose end of the bag and placing a stiff corrugated piece of leather, f, or other suitable material along and in front of the slot g, thus forming a series 80 of vertical tubes. The section f preferably extends above the slot a sufficient distance to prevent the escape of the grain through the intervening space.

While I have shown my invention as applied to that form of feed-bags which are supported at both ends, so that the position of the feed in the bag may be controlled by the movements of the animal, I do not intend to confine the application of the ventilator to 90 such bags, but contemplate its application to other and ordinary forms as well.

Owing to the peculiar construction of my improved ventilator, a sufficient amount of air is admitted to the nostrils of the horse to afford perfect respiration for the latter, and while the tubes are sufficiently open to prevent any possibility of clogging by reason of

the accumulation of feed, as is common in ventilators as heretofore constructed, their upright position prevents the escape and loss of the feed through them.

5 I am aware that it is not new to combine a ventilator with a feed-bag, and I do not herein broadly claim such combination.

I claim as my invention—

A ventilator for feed-bags, consisting of one or more upright tubes secured to the front

portion of the bag and opening into the inside thereof, substantially as hereinbefore set forth.

In testimony whereof I have hereunto subscribed my name this 5th day of May, A. D. 1883.

GEORGE W. HORNE.
